F. H. BRAECKLEIN

MILK BOTTLE RECEPTACLE

Filed Aug. 14. 1925

UNITED STATES PATENT OFFICE.

FERDINAND H. BRAECKLEIN, OF BALTIMORE, MARYLAND.

MILK-BOTTLE RECEPTACLE.

Application filed August 14, 1925. Serial No. 50,340.

This invention relates to receptacles designed to be secured within a door way or other opening to receive articles in a safe and sanitary manner without requiring the 5 householder to personally receive said articles.

Another object of the invention is the provision of a receptacle for this purpose having one of its walls formed by the door 10 or other closure of the opening, the securing means for the receptacle permitting of its ready removal when desired, as well as permitting the receptacle to be secured at either side of the door way or opening.

Another object of the invention is the provision of a novel means for locking the receptacle, so that the latter may be left open to receive the delivered article and thereafter closed and locked without the use of 15 a key, the character of the lock being such that further manipulation will neither unlock the lock or injure its mechanism.

Another object of the invention is to construct the receptacle so as to accommodate 20 a door sill or stop strip, the means for this purpose further acting to prevent entrance of water into the receptacle.

With the above and other objects in view, the invention further includes the following 25 novel features and details of construction to be hereinafter more fully described, illustrated in the accompanying drawings and pointed out in the appended claims.

In the drawings: 30

Figure 1 is a fragmentary perspective view illustrating the use of the invention.

Figure 2 is a vertical sectional view of the same.

Figure 3 is an enlarged fragmentary section illustrating the means for locking the 35 hinged cover.

Figure 4 is an enlarged fragmentary section taken substantially on the line 4—4 of Figure 3 with the locking member in retracted position.

Figure 5 is a similar view with the locking member in active position.

Referring to the drawings in detail wherein like characters of reference denote corresponding parts, the reference character 10 indicates a receptacle which is open at its rear and which may be made of suitable size and shape, the receptacle being especially designed to receive bottled milk, although it

may be used for various other articles. The 55 receptacle is provided with a cover or lid 11 which is hingedly secured to a strip 12 extending across the rear of the receptacle, the hinge being indicated at 13. The front edge of the cover is preferably provided 60 with a flange 14 engaged over the upper open edge of the receptacle. This last mentioned edge of the receptacle is provided with an inwardly extending flange 15.

Slidingly secured to the under face of 65 the cover 11 upon a pin or headed stud 16 is a locking element or bolt 17. This bolt is provided with a slot 18 to receive the stud 16 and has one of its ends offset as shown at 19 to engage beneath the flange 15. When so engaged, the lid will be securely locked. The opposite or inner end of the bolt 17 is provided with oppositely extending arms 20 which are shaped so that one edge of these arms define a curved edge 70 21 for engagement by an actuating member 22. The member 22 is substantially elliptical so as to provide a cam at each end thereof. The member 22 is mounted for rotation upon a post or stud 23 which extends 75 through the cover 11 and which carries an operating member or finger piece 24.

By rotating the actuating member 22 as indicated by the dotted lines in Figure 5 of the drawings, the locking element or bolt 17 80 will be moved from its inactive position as shown in Figure 4, to its active or locking position as illustrated in Figure 5. Further rotation or operation of the actuating member 22 will not effect the bolt 18 so that any 85 unauthorized operation of this member will not unlock the cover. Further, the construction is such that this unnecessary operation of the actuating member will not injure the lock. In order to retract the bolt to open 90 the cover it is necessary to reach inward from the open rear face and to facilitate retraction of the bolt. The latter is provided with a finger piece or lug 24a.

Extending along the lower edge of the 100 open face of the receptacle is an upwardly inclined flange 25. This flange provides space for the accommodation of a door stop or sill 26. In addition, it prevents the flow of water into the receptacle from the door 105 sill 27 or other support.

The invention is illustrated as secured to the frame 28 of the door 29, but it is of

course apparent that it may be secured within an opening of some other type.

In order to secure the receptacle in place there is provided spaced key hole slots 30 which are adapted to receive headed pins or studs 31 extending from the door frame 28.

- It is preferred to form the slots 30 in the opposite sides of the receptacle without removing the material as indicated at 32 and when it is desired to secure the receptacle in place, the material from the slots upon one side is removed while the material within the slots upon the opposite side remains.
- 15 The device may thus be arranged at either side of an opening.

It will be apparent from the foregoing description and the accompanying drawings that the invention provides a convenient device which may be attached in place to receive and hold delivered articles in a safe and sanitary condition. When it is desired to remove the receptacle, the latter may be disengaged from the studs 31 and conveniently carried by means of the strip 12.

The invention is susceptible of various changes in its form, proportions and minor details of construction and the right is herein reserved to make such changes as properly fall within the scope of the appended claims.

Having described the invention what is claimed is:

1. In combination with a receptacle having an open back and a hinged cover, a locking element carried by the cover, means at the upper edge of the receptacle adjacent the free edge of the cover for engagement by the locking element to hold the cover in closed position, an operating member upon the outside of the cover and an actuating member associated with and controlled by the operating member to force the locking element into locking position and out of the path of movement of said actuating member.

2. In combination with a receptacle having an open back and a hinged cover, a slidingly mounted locking element carried by the cover, means at the upper edge of the receptacle adjacent the free edge of the cover for engagement by the locking element to hold the cover in closed position, a member mounted for free rotation beneath the cover to contact the locking element and move the latter into locking position only and means upon the outside of the cover and associated with the rotatable element to actuate the latter.

In testimony whereof I affix my signature.

FERDINAND H. BRAECKLEIN.
